(57) **CLAIM**

The ornamental design of the memory card reader casing, substantially as shown and described.

DESCRIPTION

FIG. 1 is a top plan view of the invention;

FIG. 2 is a front elevational view;

FIG. 3 is a right side elevational view;

FIG. 4 is a left side elevational view;

FIG. 5 is a rear elevational view;

FIG. 6 is a bottom plan view;

FIG. 7 is a top plan view of a first alternate embodiment of the invention;

FIG. 8 is a front elevational view of the same;

FIG. 9 is a right side elevational view of the same;

FIG. 10 is a left side elevational view of the same;

FIG. 11 is a rear elevational view of the same; and,

FIG. 12 is a bottom plan view of the same.
